UNITED STATES PATENT OFFICE.

ALBERT B. BLY, OF DES MOINES, IOWA.

CALCULATING APPARATUS.

1,032,322.

Specification of Letters Patent. Patented July 9, 1912.

Application filed September 28, 1911. Serial No. 651,834.

To all whom it may concern:

Be it known that I, ALBERT B. BLY, a citizen of the United States, residing at Des Moines, in the county of Polk and State of Iowa, have invented a certain new and useful Calculating Apparatus, of which the following is a specification.

The object of my invention is to provide an improvement on a device of my former Patent, No. 770,552 of Sept. 20, 1904, where-
10 by the support in which the rest of the calculating device is mounted, is provided with a pivoted indicator adjacent to each of the channels in which the movable belts travel and whereby each movable belt is provided
15 with means for moving said indicator at the proper time for indicating that a figure should be carried from one column to another, which means for moving the indicator is on the opposite side of the belt from the side which receives the means for moving the belt.

A further object is to provide suitable means for visibly indicating that a figure should be carried from one column to another.

A further object is to provide suitable means whereby each movable belt may be easily and quickly returned to the zero or starting point after a calculation has been made.

My invention consists in certain details, in the construction, arrangement, and combination of the various parts of the device, whereby the objects contemplated, are attained, as hereinafter more fully set forth, pointed out in my claims and illustrated in the accompanying drawings, in which:—

Figure 1 shows a top or plan view of the 40 device embodying my invention. Fig. 2 shows a vertical, sectional view on the line 2—2 of Fig. 1 with the device for returning the movable belts to the starting point installed in position. Fig. 3 shows a vertical, 45 sectional view on the line 3—3 of Fig. 1.

In order to explain the working of my improvement I shall briefly describe the construction of my calculating device.

In the accompanying drawing I have used 50 the reference numeral 10 to indicate a rectangular frame. Within said frame are alternate filler blocks 12 and partition strips 13 extending from the top to the bottom of the frame. The partition strips 13 extend 55 downwardly below the surface of the blocks 12 and also extend upwardly above the

blocks 12 thereby forming channels 16 between their respective sides, and are also provided with laterally extending flanges 14 on the upper sides of the device, which flanges are spaced apart from the blocks 12, thus leaving grooves on each side of the channels 16, on the upper side of my device. On the upper surface 17 of each of the strips 13 I have provided a series of numerals beginning with 1 at the bottom and continuing consecutively to 9 at the top as shown in Fig. 1. Transverse shafts 21 are rotatably mounted in the ends of the frame, and rollers 20 are rotatably mounted on the 60 shafts 21 at the end of each channel 16. In the channels between the strips 13 on the upper surface of the supporting frame 10 are a series of result numerals beginning with 0 at the top and running consecutively 65 to 9 at the bottom. In the channels between the strips 13, I have provided endless belts 18 provided with perforations 19 spaced apart from each other the same distance that the numerals on the upper surface 17 are 70 spaced apart from each other. In the movable belts 18 are openings 22 spaced apart from each other ten times the distance between two adjacent openings 19. Adjacent to each of the openings 22 is an upwardly 75 extending lug 23 mounted on the belts 18. The openings 19 are located approximately 80 in line, near the right side of each of the belts 18 and the lugs 23 are located approximately 85 in line near the left side of said belt.

Located on each of the surfaces 17 at the lower end of the supporting frame 10 except on the surface 17 at the right side of the device is a pivotally mounted indicator 90 24. Each of the indicators 24 has two arms normally arranged so that one arm extends partially across the channel at the right of the indicator and so that the other arm is above the surface 17 adjacent to the channel 100 on the left. When the first arm is moved downwardly, the other arm will be moved to extend over the channel at the left of the switch.

I prepare my device for calculations by 105 bringing all the movable belts to position where an opening 22 in each is over the 0 at the upper end of each channel 16.

In operating the device as, for instance, in adding 56 and 98 the process is as follows: A suitable instrument is inserted in 110 the opening 19 adjacent to the 6 in the unit

column on the surface 17 and the belt is moved downwardly till it can be moved no farther without inserting the instrument in another opening 19. The opening 22 which was over the 0 in the unit column will then disclose the 6 in said column. The instrument is then inserted in the opening 19 opposite the 5 in the tens column and the movable belt is moved downwardly as far as possible. The opening 22 in the belt, which originally registered with the 0 in the tens column will then register with the 5 in said column. To add the 98, the instrument is then inserted in the opening 19 in the unit column adjacent to the numeral 8 and the movable belt moved downwardly as far as possible. The opening 22 which, at the beginning of the operation, registered with the 0 will pass below the series of numerals in the channel 16 and around the end of the device. The next opening 22 will move to position where it registers with the 4 in the unit column. When the first opening 22 passes around the end of the device, the lug 23 adjacent to said opening 22 on the belt, strikes the projecting arm of the indicator 24 which normally projects over the channel 16 and moves said arm downwardly. The other arm of said indicator is moved to position extending over the next channel on the left. Whenever the indicator 24 stands in the last named position, it indicates to the user of the device that a number should be carried from the column on the right to the column on the left. This is done by inserting the instrument into the opening 19 just above the indicator in the belt in the channel on the left of said indicator and moving said belt downwardly. The instrument in moving the belt will strike the arm extending over the channel on the left and return the indicator to normal position. The opening 22 will move one space in the ten column and in the illustration now being described, will move from the 5 to the 6 in the tens channel. The instrument is then inserted in the opening 19 adjacent to the 9 in the tens column and the belt 18 moved downwardly as far as possible. The opening 22 which was originally over the 0 in the tens column will move around the lower end of the device and the next opening 22 in the tens column will move to position to register with the 5 in the bottom of the tens channel. When the opening 22 passes around the end of the device, the lug on the belt adjacent to said opening strikes the projecting arm of the indicator on the left of the tens channel and moves it downwardly. The other arm on said indicator is moved out over the hundreds channel indicating that a number should be carried from the tens to the hundreds column. The instrument is placed in the opening 19 above the indicator in the hundreds column and the belt moved down-

wardly. The opening 22 is thus moved downwardly. The opening 22 is thus moved from the 0 to the 1 in said column. The openings 22 will then register with the 1 in the hundreds column, the 5 in the tens column and the 4 in the units column, showing the result of the addition:— $56+98=154$. This process of addition may be carried on indefinitely. It is noted that when in normal position the indicator arms are never in the path of the instrument by which the belts are moved, but when not in said position one arm of the indicator extends to the left into said path so that the movement of the instrument in the channel at the left of the indicator, in carrying a number forward, returns the indicator to normal position. 70 75 80

It will be noted from the description hereinbefore set forth that when the openings 22 are over the zeros in the channels 16, the next opening 22 in the same movable belt and the lug 23 thereon will be located just below the indicator 24. It is therefore clear that by moving one of the lugs 23 to position just below the switch, the belt on which said lug is located will be in proper position to begin calculations. 85 90

For quickly and easily moving the belts to proper position for beginning calculation, and for setting the indicators in normal position, I have provided the following device:—A bar 25 is provided with lugs 26 spaced apart from each other at such distances that when the said lugs are inserted into the channels 16 adjacent to the left sides thereof as shown in Fig. 2, and are moved from the upper end to the lower end of said channels, the lugs 26 will engage the lugs 23 on the respective movable belts, and move them to position just below the switch and all of the movable belts will be in proper position for beginning calculations. The lugs 26 are narrow enough that when moved down the left sides of the channel they will not interfere with indicator arms extending over the channel from the right side thereof. By the above operation the indicators 24 will be moved from their normal positions. To move the indicators to normal position, I move the lugs 26 to positions adjacent to the right sides of the channels 16 and move them downwardly, striking the arms of the indicators 24 and moving said indicators to their normal positions. I preferably provide on one end of the bar 25, a projecting point 27 suitable for entering the opening 19 and moving the belts 18. 100 105 110 115 120

In the practical operation of my improved device, the lugs 26 on the bar 25 are placed in the channels 16 adjacent to the left sides thereof at the upper ends of the said channels and are then moved toward the lower ends so that one of the lugs 23 on each of the movable belts 18 is moved to po- 125 130

sition just below the switch. An opening 22 in each of said movable belts will then be over the 0 in the channel 16. The indicators are then moved to normal position as above set forth. The process of adding may 5 then be carried on as hereinbefore described and as more fully set forth in my former patent. The indicator 24 adjacent to each movable belt will be turned at the proper time to indicate that a number should be carried to the column on the left. That 10 figure may be carried forward as hereinbefore described and the process may be carried on indefinitely.

15 My improved device herein described, has the advantages, when used with my calculating device, of visibly indicating when a number should be carried forward and it also indicates visibly by the position of the 20 switch that the process of carrying forward has been completed.

I claim as my invention:—

1. In a device of the class described, a frame having channels therein, endless belts 25 movably mounted in said channels, means for engaging the belts, said means being located on one side of said belts, lugs on the other side of said belts and an indicator mounted on said frame between said channels, having an arm which in one position of its movement extends into the path of 30 said lugs, on one belt and another arm, which in one position of its movement extends into the path of the means for engaging another belt.

35 2. In a calculating device, a supporting frame having channels therein, a series of result numerals in said channels, a series of numerals adjacent to said channels, endless

belts movable in said channels having openings therein designed to disclose said result numerals, means for engaging said belts for moving them, lugs on said belts, indicators located on said frame having portions designed to extend partially across the next 45 channel on the right into the path of said lugs but not into the path of said means for engaging said belts.

3. In a device of the class described, a frame, channels formed therein, endless 50 belts movably mounted in said channels, means located adjacent to one side of each of said belts whereby said belts may be moved, lugs on the other side of each of said belts, indicators movably mounted between 55 said channels, each indicator being constructed with one arm which in its normal position extends partially across the channel at the right of the indicator into the path of said lugs, and another arm which normally rests over the portion of the device between the channels but which is moved to position extending partially across the channel at the left when the other arm is struck by the lugs on the belt in the channel 60 on the right.

4. In a device of the class described, a bar provided with lugs properly located and projected into the channels of the calculating device so that when moved downwardly 70 therein they will engage the lugs on the movable belts.

Des Moines, Iowa, Sept. 15, 1911.
